PUMP

Peter D. George, Stratford, Conn., assignor, by mesne assignments, to Textron Inc.

Filed Aug. 11, 1966, Ser. No. 3,425

Term of patent 14 years

(Cl. D65—1)

FIG. 1 is a side perspective view showing my new design for a pump.

FIG. 2 is a front perspective view thereof.

FIG. 3 is a rear elevational view thereof.

FIG. 4 is a rear-side perspective view thereof.
The tubes shown in broken lines are included for illustrative purposes only.

I claim:

The ornamental design for a pump, as shown.
